DESIGN FOR A CASSEROLE COVER OR SIMILAR ARTICLE

Arthur P. Miller and John Clifford Hestwood,
New Kensington, Pa., assignors to The Aluminum
Cooking Utensil Company, New Kensington,
Pa., a corporation of Pennsylvania

Application June 24, 1941, Serial No. 101,636

Term of patent 7 years

To all whom it may concern:

Be it known that we, Arthur P. Miller and John Clifford Hestwood, citizens of the United States, residing at New Kensington, in the county of Westmoreland and State of Pennsylvania, have invented a new, original, and ornamental Design for a Casserole Cover or Similar Article, of which the following is a specification, reference being had to the accompanying drawing, forming a part thereof, in which:

Fig. 1 is a top plan view of a casserole cover or similar article, showing our new design; and

Fig. 2 is a view thereof partially in elevation and partially in section.

The material of the casserole cover is transparent, with translucent stippled areas indicated by shaded portions in the drawing.

We claim:

The ornamental design for a casserole cover or similar article, substantially as shown and described.

ARTHUR P. MILLER.
JOHN CLIFFORD HESTWOOD.
